Atty:

UNITED STATES PATENT OFFICE.

CHARLES A. STOCKSTROM AND LOUIS STOCKSTROM, OF ST. LOUIS, MISSOURI.

DESIGN FOR A GAS OR VAPOR STOVE.

SPECIFICATION forming part of Design No. 18,257, dated April 10, 1888.

Application filed October 18, 1887. Serial No. 252,764. Term of patent 14 years.

To all whom it may concern:

Be it known that we, CHARLES A. STOCKSTROM, a citizen of the United States, and LOUIS STOCKSTROM, a subject of the Emperor of Germany, and residents of St. Louis, in the State of Missouri, have invented and produced a new and original Design for Gas or Vapor Stoves, of which the following is a specification, reference being had to the accompanying drawing, forming part of this specification, which represents a perspective view of a stove of our design.

The leading feature of our design is the rectangular body located at one end of the stove. 1 represents the flat table of a stove-frame; 2, skeleton legs thereof; 4, skeleton burner-plates; 5, a rectangular body over the skeleton

extension; 7, a bent arm extending from beneath the flat table to a position beneath the body and an enlargement, 6, on the outer end 20 of the arm.

Having thus described our design, the following is what we claim as our invention and desire to secure by Letters Patent:

The design for a gas or vapor stove herein shown and described, the same consisting of a skeleton frame, a table, and a rectangular body at the end of the frame, substantially as set forth.

CHAS. A. STOCKSTROM.
LOUIS STOCKSTROM.
